US0D1065016S

(12) **United States Design Patent** (10) Patent No.: **US D1,065,016 S**
(45) Date of Patent: ** Mar. 4, 2025

(54) **BICYCLE WATER BOTTLE HOLDER**

(71) Applicant: **Lian Wang**, Hunan (CN)

(72) Inventor: **Lian Wang**, Hunan (CN)

(**) Term: **15 Years**

(21) Appl. No.: **29/975,293**

(22) Filed: **Nov. 27, 2024**

(51) LOC (15) Cl. **12-16**

(52) U.S. Cl.

USPC **D12/411**

(58) **Field of Classification Search**

USPC D7/300, 307, 313, 602, 620; D12/114, D12/411, 413, 417, 420

CPC B62J 11/00; B62J 11/04; B62J 45/00

See application file for complete search history.

(57) **CLAIM**

The ornamental design for a bicycle water bottle holder, as shown and described.

DESCRIPTION

FIG. 1 is a perspective view of a bicycle water bottle holder showing my new design;

FIG. 2 is another perspective view thereof;

FIG. 3 is a front elevation view thereof;

FIG. 4 is a back elevation view thereof;

FIG. 5 is a left side elevation view thereof;

FIG. 6 is a right side elevation view thereof;

FIG. 7 is a top plan view thereof; and,

FIG. 8 is a bottom plan view thereof.

1 Claim, 8 Drawing Sheets
